ATTORNEY

UNITED STATES PATENT OFFICE.

ARTHUR S. LOSEY, OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT.

FABRIC.

Application filed August 31, 1927. Serial No. 216,563.

My invention relates to that class of fabrics that are commonly employed at the meeting edges of articles of wearing apparel, as overshoes, garments and the like, to secure 5 said edges together, and an object of my invention, among others, is the production of a fabric of simple construction that shall be particularly adapted for use in connection with the sliding devices for securing such 10 edges.

A fabric embodying my invention and in the construction and use of which the objects herein set out, as well as others, may be attained is illustrated in the accompanying 15 drawings, in which—

Figure 1 is a face view of a piece of fabric embodying my invention.

Figure 2 is a similar view, but with the scale materially enlarged, and with that portion embodying my invention distorted by being spread out to illustrate the weave.

Figure 3 is a view in section on a plane denoted by the dotted line 3—3 of Figure 2, but with that portion embodying my invention 20 in its normal condition as assumed during the weaving operation.

Figure 4 is a view similar to Figure 3 and on a plane denoted by the dotted line 4—4 of Figure 2.

Figure 5 is a view of a portion of my improved fabric with the threads broken away to show construction.

Figure 6 is a detail view illustrating the manner of use of my improved fabric.

It is common practice at the present time to close the meeting edges of openings in articles of wearing apparel and other devices by means of a metallic closing member that is slidably attached to guiding and locking strips, also usually of metal, that, in some instances, are fastened to comparatively narrow pieces separately formed and attached to the borders of the fabrics at such meeting edges, these guiding strips having interlocking means at certain points to secure the meeting edges after the sliding member has passed such point in its sliding movement.

As before stated this means of fastening is commonly employed in overshoes and other wearing apparel, as well as in other articles, wherein the meeting edges of the fabric are provided with beads or ribs to which the metallic guiding members are secured, and

which beads or ribs serve to retain said guiding and locking members in place. 55

These beads or ribs have been provided in previous structures in various ways, as by weaving a single cord into the structure to comprise the edge, but this is objectionable in that the cord does not maintain its position in the center of the edge, as the fabric often becomes distorted and the cord positions itself all on one side of the fabric.

It is of material advantage that the ribs for positioning and holding the guiding and locking strips shall be located a short distance back from the edge of the material so that such strips shall have a support on each side of the ribs, as thereby the material preserves its original shape and a rib is maintained on each side of the fabric. As the ribs have heretofore been provided, as by stitching cords on opposite sides of the fabric, it is a purpose of my present invention to provide a weave of simple character that shall result 75 in the formation of these beads or ribs opposite each other on opposite sides of the fabric and extending parallel with the edge a short distance therefrom to afford a support 80 for the guiding and locking strips on opposite sides of each rib.

To this end I make use of an ordinary weave, as to the body 6 of the fabric, which body comprises warp threads 7 and weft or filling threads 8, which threads may be disposed in various ways common to the art of weaving and which are more specifically hereininafter referred to as to the formation of the rib or bead in which they are arranged in a peculiar manner to accomplish my purpose. 90

In this formation of the fabric certain of the warp threads are brought together so that they form ribs on opposite sides of the fabric, a short distance from its edge, which fabric is in effect extended in a straight plane 95 between these ribs.

In effecting this purpose I arrange certain warp threads in two groups, each of which groups may consist of any number of warp threads, four being shown herein, as comprised in each group. One of these groups comprises the threads 9, 11, 13 and 15 and the other comprises the threads 10, 12, 14 and 16. It will be understood, however, that each group may consist of a greater or lesser number of warp threads. The threads compris- 100 105

ing each group are bunched, as shown in Figures 3, 4 and 5, this bunching being done in the weaving operation by presenting the threads in this bunched condition at the point 5 of weaving, and there securing them by means of the weft thread which is passed in one direction outside of one bunch, then in the opposite direction between the two bunches, and then in the direction first men- 10 tioned outside of the other bunch, and then back again between the two bunches, this operation being continued.

This will be readily understood from an examination of Figures 3 and 4 in connection 15 with Figure 2, in the latter of which the fabric is developed in a flat plane to show the weave, while it is in its natural state, as shown in Figures 3 and 4.

From these views it will be noted that the 20 pass 17 of the weft thread passes between the two bunches and on its return the pass 18 extends across the bunch 21. Now by noting Figure 4 it will be seen that in its next run the pass 19 extends between the two bunches 25 and on its return the pass 20 extends across the bunch 22. This order is maintained throughout the weaving thereby creating two ribs or beads 23 located on opposite sides of the body 6 near its edge. The weave is a very 30 simple one and the ribs or beads are formed simply by closing the warp threads 9, 11, 13 and 15 together, from the position shown in Figure 2, to the position shown in Figures 3 and 4, and in like manner closing the warp 35 threads 10, 12, 14 and 16 together thus forming the groups or bunches 21 and 22, and by securing these bunches thus formed by the passes 18 and 20, as shown in Figures 3 and 4 and in the manner hereinbefore described.

40 While the relative sizes of the threads are immaterial as far as the invention is concerned, yet it may be found of advantage in some instances to have the warp threads forming the groups of bunches 21-22 larger than 45 the other warp threads, and as shown in Figure 5.

It will thus be seen that I have provided a fabric with the ribs or beads formed a short distance back from the edge in the regular order of weaving, thereby obtaining a 50 supporting edge 25 for the guiding and locking strips, which strips are supported by the fabric on opposite sides of the ribs and which strips may be secured to the ribs as by pinching and setting them around the ribs, and as 55 shown in Fig. 6 of the drawing. Said strips therefore maintain their position on the fabric in a manner to enable the closing member 60 to be readily slid along the strips for fastening or unfastening purposes.

In accordance with the provisions of the patent statutes I have described the prin-

ples of operation of my invention, together with the device which I now consider to represent the best embodiment thereof; but I desire to have it understood that the article shown is only illustrative and that the invention may be carried out by other means and applied to uses other than those above set out.

I claim—

1. The combination with a fabric comprising a set of warp and a set of filling threads and having a rib extending along one edge and formed of a plurality of one of said sets 75 of threads bunched together in contact one with another throughout their lengths and secured in this condition by threads of the other of said sets extended across the bunch to form said rib, of a guiding and locking strip secured by said rib, and a closing member 80 slidable along said strip.

2. The combination with a fabric having a rib extending along one edge and formed of a plurality of warp threads bunched together 85 in contact one with another throughout their lengths and secured in this condition by weft threads extended across the bunch to form said rib, of a guiding and locking strip secured by said rib, and a closing member 90 slidable along said strip.

3. The combination with a fabric having 95 ribs on opposite sides thereof and extended along its edge, said ribs each being formed of a plurality of warp threads bunched together in contact with each other throughout their lengths and separated by weft threads extended between and over the bunches to hold the threads of each bunch together, of a guiding and locking strip secured by said rib, and 100 a closing member slidable along said strip.

4. The combination with a fabric having 105 ribs on opposite sides thereof extending in parallelism with but spaced from one edge, said ribs being formed by warp threads and said ribs being disposed on opposite sides of the fabric, and said ribs being secured by transverse threads extended across outside of the ribs, of a guiding and locking strip secured by said rib, and a closing member 110 slidable along said strip.

5. The combination with a fabric having 115 ribs on opposite sides thereof formed of warp threads secured by weft threads extended around said warp threads to tie them and across, between said ribs on opposite sides of the fabric and beyond the ribs to form a support between the ribs and the edge of the fabric for a guiding and locking strip, of a guiding and locking strip secured by said rib, and a closing member slidable along said strip.

ARTHUR S. LOSEY.
